C. A. HONES,

AUTOMATIC BLAST SOLDERING FURNACE.
APPLICATION FILED FEB. 10, 1920.

1,381,836.

Patented June 14, 1921.

UNITED STATES PATENT OFFICE.

CHARLES A. HONES, OF ROSEDALE, NEW YORK.

AUTOMATIC BLAST SOLDERING-FURNACE.

1,381,836.

Specification of Letters Patent. Patented June 14, 1921.

Application filed February 10, 1920. Serial No. 357,545.

To all whom it may concern:

Be it known that I, CHARLES A. HONES, citizen of the United States, and resident of Rosedale, in the county of Nassau and State 5 of New York, have invented certain new and useful Improvements in Automatic Blast Soldering-Furnaces, of which the following is a specification.

This invention relates to an automatic 10 blast soldering furnace. Its object is the production of a furnace that can be easily secured in place, and which is made of detachable parts that lock together, and which consequently can be easily cleaned. It has 15 connected thereto a pilot light, by virtue of which the flame of the burner of the furnace can be turned off when work to be operated upon is being assembled, or when the furnace is not in actual use.

20 The well of the furnace is provided with a detachable abrasive rest, which protects the points of soldering irons and keeps them clean. The rest also prevents the tinning being drawn from the soldering irons.

25 The furnace can be made with one or a plurality of Bunsen burners, and is particularly useful for plumbing, electrical machine and general shop work.

In the drawings Figure 1 represents a top 30 plan view of an exemplification of the improved furnace; Fig. 2 shows a fragmentary top plan view of some of the parts of the furnace; Fig. 3 is a section of Fig. 1 approximately on the line 3, 3; Fig. 4 shows 35 a left hand side view of a portion of Fig. 1; Fig. 5 represents a left hand view of Fig. 4; Fig. 6 shows a perspective view of a rest for the furnace and Fig. 7 represents a perspective view of the hood of the furnace.

40 The furnace is represented with the table 20, having formed therewith the well 21 with the inclined front wall 22, the inclined rear wall 23 with the lugs 24 and the side 45 walls 25 with the flanges 26 extending from the inside faces of the latter. An opening 30 in the rear wall 23 has pivoted therewith over a swinging door 31. A stop pin 32 extends from the outer face of the wall 23 to 50 enable the door 31 to rest thereon when the opening 30 is to be maintained open. In the front wall 22 is formed the opening 33 to supply air for combustion. A pair of rear legs like 36 extend from a connecting brace 55 37 and have formed therewith feet 38. Each

of the latter has formed therein the elongated opening 39. Bolts 40 connect the brace 37 to the outer face of the well 21. In each of the legs 36 are formed elongated 60 openings 41. A pair of front legs 44 extend from a connecting brace 45 and have formed therewith the feet 46 with the elongated 65 openings 47. Bolts 48 connect the brace 45 to the bottom face of the front portion of the table 20. In each of the legs 44 are 70 formed elongated openings 49 similar to 41.

Gas supply piping is shown to comprise the side portion 52 and front end portion 53. Clamps 54 secure the portion 52 to the legs 36 and 37. The clamps 54 are of novel 75 construction and each comprises the legs 55 with the heels 56. A U shaped member 57 connects the legs 55. Bolts 58 extend through the legs 55 and through the openings 41 and 49 to detachably clamp the legs 55 to the legs 36 and 44. A pair (in this instance) of Bunsen burners 61 extend upwardly and rearwardly from the front portion 53 of the gas supply piping through 80 openings in the front wall 22 in the well 21. Gas cocks 62 are provided for the burners. A pilot light 63 with an adjusting valve 64 extends from the portion 53 of the gas supply piping. An abrasive rest 65 in this instance of fire brick with the 85 inclined corrugated table or top face 66 is located in the well 21 between the rear wall 23 and the flanges 26. A detachable hood 68 which performs the function of a combustion chamber comprises 90 the rear wall 69, the front wall 70 with the opening 71, the side walls 72 each with an inner projecting lug 73 and an outer projecting lug 74. The hood 68 bears upon the table 20 and detachably locks therewith by 95 means of the said lugs 73 and 74. A melting or solder pot 78 has formed therewith the curved bottom 79 and from the outer surface of the latter extend lugs 80 which lock with the upper portions of the walls of the 100 hood 68.

To use the furnace a soldering iron or other object to be heated is located through the opening 71 with its end bearing on the table 66 of the rest 65, and at the same time 105 lead or other material may be melted in the melting pot 78. If desired the rest 65 may be removed and an object may be located in the well 21 and extend through the openings 30 and 71.

Having described my invention what I desire to secure by Letters Patent and claim is:

1. In a furnace the combination of a table having a well formed therewith, legs for the table and well, gas supply piping for the furnace, detachable brackets connected to a pair of said legs supporting said piping, a Bunsen burner connected to the gas supply piping and extending into the well and 10 a pilot light for the burner.

2. In a furnace the combination of a table having a well formed therewith, a pair of legs supporting said well and a pair of legs supporting the front end of the table, gas 15 supply piping for the table, a detachable bracket connected to one of each pair of the legs supporting said piping, a Bunsen burner extending upwardly and rearwardly from the said piping at the front portion of the 20 burner into said well, a pilot light extending from said piping into the well and an abrasive support with an inclined top face located in said well.

3. In a furnace the combination of a table 25 having a well formed therewith, a pair of legs connected to the rear portion of the well, a pair of legs connected to the front portion of the table, gas supply piping for the furnace, a detachable bracket connected to one 30 of each pair of the legs supporting said piping, a Bunsen burner extending upwardly and rearwardly from said piping at the front portion of the burner into said well, a pilot 35 light extending from said piping into the well, a detachable hood locked to the table over the well and a melting pot locking with and detachably supported on the hood.

4. In a furnace the combination of a table 40 having a well formed therewith, a pair of legs having a pair of elongated openings formed therein connected to the rear portion of the well, a pair of legs having a pair of elongated openings connected to the front portion of the table, gas supply piping with 45 a side portion located parallel to the side of the table and a front end portion parallel to the front end of the table for the furnace, a pair of detachable brackets for one of each of said pairs of legs supporting said 50 gas piping, each of said brackets comprising a pair of legs having each a heel to engage an

edge of its accompanying leg, a U shaped member connecting the legs of each bracket, bolts extending through the legs of each bracket and through the elongated openings 55 in its accompanying leg of the table to secure the bracket to the leg and hold the side portion of the gas supply piping in place, a Bunsen burner connected to the front end portion of the piping extending upwardly 60 and rearwardly into the well of the table and a pilot light for the burner extending from the piping into said well.

5. In a furnace the combination of a table 65 having a well formed therewith, legs supporting the table and well, gas supply piping for the furnace detachably connected thereto and Bunsen burners connected to the piping and extending into the well.

6. In a furnace the combination of a table 70 having a well formed therewith, detachable legs supporting the table and well, gas supply piping for the furnace detachably connected thereto, Bunsen burners connected to the piping and extending into the well 75 and an abrasive rest in the well.

7. In a furnace the combination of a table 80 having a well formed therewith, detachable legs supporting the table, gas supply piping for the furnace, detachable brackets connected to the legs supporting said piping, Bunsen burners connected to the piping and extending into the well and an abrasive rest with an inclined corrugated top face located 85 in the well.

8. In a furnace the combination of a table 90 having a well formed therewith, legs supporting the table and well, gas supply piping extending on one side and one end of said table, detachable brackets connected to the legs supporting said piping, Bunsen burners connected to the piping extending into the well, a pilot light for the burners, a hood detachably supported on the table over the well, a melting pot detachably supported on the hood and an abrasive rest in 95 the well.

Signed at New York, in the county of New York and State of New York, this 24th day of January, A. D. 1920.

CHARLES A. HONES.
